UNITED STATES PATENT OFFICE.

ROSE RICE TURNER AND JOHN CHARLES BERNITT, OF SPOKANE, WASHINGTON.

ELECTRICAL KEYBOARD-HEATER AND TONE-PRESERVER FOR PIANOS AND ORGANS.

No. 861,560.

Specification of Letters Patent.

Patented July 30, 1907.

Application filed March 7, 1906. Serial No. 304,633.

To all whom it may concern:

Be it known that we, ROSE RICE TURNER and JOHN CHARLES BERNITT, citizens of the United States, residing at Spokane, in the county of Spokane, State of Washington, have jointly invented a new and useful Electrical Keyboard-Heater and Tone-Preserver for Pianos and Organs, of which the following is a specification.

Our invention relates to the application of heat to the keyboard and principal mechanism of the instrument by means of an electrical heater, and the objects of our invention are: first, to warm the keys of the instrument, and second, to reduce the moisture in the instrument. We attain these objects by the installation of the electrical heater under the keyboard of the piano or organ as illustrated in the accompanying drawing, in which

Figure I is a top view of the keyboard of a piano or organ as it appears after the removal of a number of the keys and the installation of the electrical heater. Fig. II is a vertical section of the same with the electrical heater therein.

Similar letters refer to similar parts throughout the several views.

The resistance of the heater is distributed in such a manner as principally to warm the front part of the keys and the principal mechanism of the instrument as shown by the drawings. As resistance, may be used Germansilver, copper, or iron wire, and as insulator asbestos, rubber, mica, or some other non-conductor.

For the purpose of illustrating the accompanying drawing we will use Germansilver wire and asbestos as resistance and insulator respectively. The resistance creating the heat is distributed in the following manner:

For the application of an electrical current of about 110 volts, use about 250 feet of No. 22 Germansilver wire, of which about 45 feet are placed in coil A, Fig. I, which is located underneath the keys, F, in front of the first row of iron pegs or guide pins, G, the full length of the keyboard. About 65 feet of wire is placed in coil B, which is located underneath the keys between the two front rows of iron pegs, G and H, that is, the guide pins G, and balance pins H. The balance of the wire is equally distributed in three coils C D and E, placed between the second row of iron pegs and the principal mechanism of the instrument.

As shown in Fig. I at a', b', c', d', and in Fig. II at a³, b³, c³, d³ coil B consists of one layer of asbestos on

the top of the key-board, a', one layer of wire, b', one layer of perforated asbestos, c', and one layer of wire, d'. 50 Coil A is constructed the same as coil B, as shown in Fig. I at a², b², c², d². The electrical current enters coil A in the upper layer of wire and also passes through the lower layer of wire of the coil same; next enters the upper layer of coil B and also passes through the lower 55 layer of the same coil, and from there passes through coils C, D and E in series.

In order to regulate the heat, instal controller, J Fig. I, increasing the heat by moving lever f from connection g to connection h, which cuts out coil E, and 60 further increasing the heat by moving the said lever to connection i, cutting out coil D, practically as shown in said drawings.

The heater may be manufactured for the use of any voltage-current by simply changing the resistance of 65 the heater correspondingly.

For large church organs where a larger space has to be heated, the heater will be arranged in two or more sections and connected up in multiple.

What we claim as our invention and for which we desire to secure Letters Patent, is:

1. An electrical heating device for use in pianos and organs, a heater B, consisting of one layer of insulating material on the top of the key-board a', one layer of coiled resisting wire b¹, one layer of perforated insulating material c¹, and one layer of resisting wire d¹; a heater A, under the keys and in front of the guide pins G, constructed in the manner and of the same material as said heater B, and coils C, D and E, of resisting wire at the rear of said coils B and A, said coils heated by an electric battery, substantially as shown and described, and for the purposes set forth. 75

2. An electrical heating device for use in pianos and organs, a heater B, consisting of one layer of insulating material on the top of the key-board a', one layer of coiled resisting wire b¹, one layer of perforated insulating material c¹, and one layer of resisting wire d¹; a heater A, under the keys and in front of the guide pins G, constructed in the manner and of the same material as said heater B; coils C, D and E, of resisting wire at the rear of said heaters B and A, and a heat controller J, adapted to regulate the heat, substantially as shown and described, and for the purposes set forth. 90

In testimony whereof we have signed our names to this specification in the presence of two subscribing witnesses. 95

ROSE RICE TURNER.
JOHN CHARLES BERNITT.
